(57) **CLAIM**

I claim the ornamental design for a ball display case, as shown and described.

DESCRIPTION

FIG. 1 is a perspective view of a ball display case showing the new design, shown with balls displayed therein.

FIG. 2 is a perspective view thereof, shown empty.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a perspective view of an alternative embodiment of a ball display case, shown with balls displayed therein.

FIG. 10 is a perspective view thereof, shown empty.

FIG. 11 is a front view thereof.

FIG. 12 is a rear view thereof.

FIG. 13 is a left side view thereof.

FIG. 14 is a right side view thereof.

FIG. 15 is a top view thereof.

FIG. 16 is a bottom view thereof.

FIG. 17 is a perspective view of an alternative embodiment of a ball display case, shown with balls displayed therein.

FIG. 18 is a perspective view thereof, shown empty.

FIG. 19 is a front view thereof.

FIG. 20 is a rear view thereof.

FIG. 21 is a left side view thereof.

FIG. 22 is a right side view thereof.

FIG. 23 is a top view thereof; and,

FIG. 24 is a bottom view thereof.

In the drawings, the broken lines shown in the figures depict unclaimed subject matter and/or environmental structure, and form no part of the claimed design.

1 Claim, 24 Drawing Sheets
